UNITED STATES PATENT OFFICE.

FREDRICK G. ROGERS, OF BUFFALO, NEW YORK.

CLEANER FOR STEAM-BOILERS.

No. 851,694.

Specification of Letters Patent.

Patented April 30, 1907.

Application filed March 18, 1906. Serial No. 305,784.

To all whom it may concern:

Be it known that I, FREDRICK G. ROGERS, a citizen of the United States, residing at Buffalo, in the county of Erie and State of New York, have invented a certain new and useful Improved Cleaner for Steam-Boilers, of which the following is a specification.

This invention relates to an improved cleaner for steam boilers and particularly to a device for purifying the water.

The object of the invention principally is to prevent the formation of scale and consequently maintain a uniform boiler heating capacity, economize in fuel consumption, and obviate any danger from uneven over-heating of the boiler surface.

The invention also relates to certain details of construction, all of which will be fully and clearly hereinafter described and claimed reference being had to the accompanying drawings, in which,—

Figure 1, is a vertical longitudinal section through a furnace and boiler equipped with my improved purifying device. Fig. 2, represents in one half a front elevation of, and in the other half, a transverse vertical section through a furnace and boiler equipped with the improved purifying device on line *a—a*, Fig. 1. Fig. 3, is an enlarged vertical transverse section through the boiler proper, or main water chamber of a water tube boiler, provided with the improved purifying device, on line *a—a*, Fig. 1. Fig. 4, is an enlarged fragmentary bottom view of the blow out pipe for removing the impurities from the purifying device. Fig. 5, is a detached enlarged top plan view of the preferred form of purifying device. Fig. 6, is a vertical longitudinal section on line *b—b*, Fig. 5. Fig. 7, is an enlarged vertical transverse section on line *c—c*, Fig. 6, looking in the direction of the arrow *V*. Fig. 8, is an enlarged detached bottom view of one of the lower partitions. Fig. 9, is an enlarged vertical transverse section on line *d—d*, Fig. 6, looking in the direction of the arrow *X*. Fig. 10, is an enlarged detached top view of one of the upper partitions. Fig. 11, is an enlarged vertical transverse section on line *e—e*, Fig. 6, looking in the direction of the arrow *Z*.

In referring to the drawings for the details of construction of the preferred adaptation of my invention therein shown, like numerals designate like parts.

While the form of the improved purifier shown is particularly adapted to be used in

conjunction with a water tube boiler of the type illustrated, it may, with some slight changes, be employed in any of the well known styles of boilers.

The boiler is mounted in a furnace or heater 1, of well known type, and comprises a main cylindrical water chamber or tank 2, located in the upper portion of the furnace and extending horizontally and longitudinally through the furnace from the front to the back thereof, a series of diagonally extending longitudinal tubes 3, arranged below the main water chamber 2, and connected at their ends by the front and rear boxes 4 and 5, which in turn are connected to the main water chamber 2, by pipes 6 and 7, so that a continual circulation of water is maintained through the boiler parts when the furnace or boiler is running.

A mud drum 8, is located in the lower rear corner of the furnace which is connected to the rear box 5, by a pipe 9, see Fig. 1.

The preferred type of purifying device comprises a plurality of long troughs arranged horizontally side by side and parallel to each other. In the drawings two troughs are shown in horizontal side by side position and located in the main chamber or tank 2. To support the troughs in position, opposed brackets 10 and 11, are fastened by tap bolts 12, or other suitable means to the opposite sides of the interior of the tank, see Fig. 3, and are secured to the troughs by bolts 13, or similar fastenings.

The brackets 10 and 11, it should be noted are of a peculiar curved or angular form, having enlarged upper ends provided with flat sides which are bolted to the sides of the troughs and curved and flanged and tapering portions which conform to the curved interior surface of the tank and depend below the enlarged upper ends being fastened at suitable intervals to the tank by bolts.

By referring to Fig. 3, it will be noted that the troughs the connecting pipes and the brackets form a horizontal connection between opposite sides of the tank, thereby not only securing the troughs very rigidly in place but also decidedly strengthening and stiffening the tank itself. Another advantage is that the top and bottom of the tank is left free from obstruction for the brackets are located at and attached to the sides. This also renders the brackets very accessible by detachment or attachment.

The troughs are connected to each other at

or near one end by a transverse pipe 14, which is connected to a water inlet pipe 15, and at or near the opposite end by a transverse pipe 16, from which an outlet pipe 17, 5 extends vertically downward to near the bottom of the tank 2, see Fig. 1.

The troughs are formed from sheet metal or other suitable material. The trough, as preferably constructed, consists of a curved 10 or rounded bottom plate 18, side plates 19, and 20, which are lapped upon and fastened to the bottom plate by bolts 21, and end plates 22 and 23, each of which is secured in proper position at the respective ends of the 15 trough by bolts 24, which pass through the end plates and side and bottom plates and the connecting and supporting angle irons 25.

A series of upper and lower transverse vertical partitions 26, and 27, are located at 20 suitable intervals in the trough and in alternate arrangement so that the water will follow the sinuous path indicated by the arrows 15 in Fig. 1, in passing through the trough. The purpose of these partitions is to interrupt 25 and impede the straight flow of the water and thus secure a better precipitation of the impurities in the water to the bottom of the trough.

A blow out pipe 28, extends longitudinally 30 in the trough from near one end to and through the opposite end from whence it extends through the end of the tank 2, to any suitable locality. The blow out pipe 28, is located near the bottom of the trough being 35 supported in position by the lower partitions 27, and the end plate 23, of the trough through openings in which it extends. The end of the blow out pipe 28, within the trough is closed by a cap 29, see Figs. 1 and 4. 40 Diagonal slots or openings 30, are cut in the under surface of the blow out pipe at suitable intervals, see Figs. 4, 7 and 11, through which the settled impurities are removed 45 when the blow out cock 31, shown in Fig. 1, is opened.

It will be noted by referring to Figs. 7, 9 and 11, that the blow out pipe 28, is centrally arranged in the space formed by the curve of the bottom plate of the trough, so 50 that the impurities naturally slide gradually or move into position beneath the blow out pipe and are thus collected in the best place for quick removal.

By employing two or more troughs the 55 troughs may be made smaller in diameter so that the water will be divided into streams of comparatively small volume so that better purification is more thoroughly and quickly secured. Besides either of the troughs can be 60 quickly cleaned by opening the cock 31, of its blow out pipe 28, and thereby permitting the interior boiler pressure to force the impurities and sediment collected in the bottom of the trough out through the blow out 65 pipe.

This improved purifying device is adapted to be used with nearly all of the well known styles of boilers and is intended to remove a large percentage of the impurities from the water before it is introduced into the 70 boiler.

The operation of the invention will be readily understood from the foregoing description and drawings. In this improvement the water flows into all the troughs 75 through the transverse trough connecting pipe at one end and flows out from all the troughs through the transverse trough connecting pipe at the opposite end, thereby dividing the water into two or more smaller 80 streams of small volume each of which flows through a separate independent trough, and then reuniting the streams after their passage through the troughs. This not only increases the rapidity of the flow of water but 85 also renders the cleansing action more thorough and complete.

I claim as my invention—

1. The combination with a boiler, of a bracket having an enlarged upper end provided with a flat side and a depending tapering portion which is attached to the inner surface of said boiler and a purifying trough fastened to the flat side of the enlarged upper 90 end of said bracket.

2. The combination with a boiler, of a bracket having a depending portion attached to the inner surface of the side of said boiler and a purifying trough bolted to the upper end of said bracket.

3. The combination with a boiler, of a plurality of opposed brackets each having an enlarged upper end and a depending tapering portion, and the tapering portions of said brackets being fastened to the opposite sides 105 of the inner surface of said boiler and a purifying device fastened to the enlarged upper ends and supported from and between said brackets.

4. A purifying device for boilers consisting 110 of a curved bottom plate, two side plates, two end plates, a series of transverse partitions having curved bottom edges to correspond to the curve of the bottom plate and openings near the bottom thereof, and a longitudinal blow out pipe arranged and supported in the space formed by the curve of the bottom plate, and passing through the openings in the transverse partitions, substantially as set forth.

5. A purifying trough for boilers consisting 120 of a curved or rounded bottom plate, two side plates lapped on and bolted to the bottom plate, two end plates each bolted to and forming the respective ends of the trough, a series of upper and lower transverse partitions arranged alternately at suitable intervals, said lower partitions having curved 125 lower edges to correspond to the curve of the bottom plate and openings near the bottom 130

thereof, and a longitudinal blow out pipe located near the bottom and passing through the openings in and supported by some of the transverse partitions; one end of said blow out pipe being terminated near one end of the trough and being closed by a cap and the opposite end being extended through the opposite end of the trough and through the boiler end, and said blow out pipe being also provided on its under surface with a series of openings, substantially as set forth.

6. The combination with a boiler, of opposed curved brackets fastened to opposite sides of said boiler and a plurality of connected purifying troughs arranged side by side in said boiler and secured to the upper ends of said brackets.

7. The combination with a boiler of opposed curved tapering brackets fastened to opposite side of said boiler and a plurality of purifying troughs located in said boiler in parallel longitudinal arrangement and secured to the upper ends of said brackets.

8. The combination with a boiler, of a plu-

rality of purifying troughs arranged side by side in said boiler, transverse pipes connecting said troughs at or near each end, an inlet connected to one of said transverse pipes, and an outlet pipe extending from the other transverse pipe.

9. The combination with a boiler, of a plurality of purifying troughs arranged side by side in said boiler, transverse pipes connecting said troughs at or near each end, an inlet connected to one of said transverse pipes, an outlet pipe extending from the other transverse pipe, and an independent blow out pipe in each of the troughs.

10. The combination with a boiler, of a plurality of purifying troughs connected together to have a common inlet and outlet and an independent blow out pipe in each of the purifying troughs.

FREDRICK G. ROGERS.
